E. L. YORK,

IRONING MACHINE.

APPLICATION FILED SEPT. 22, 1919.

1,403,582.

Patented Jan. 17, 1922.

INVENTOR.
Edgar L. York.

W. J. Reck

UNITED STATES PATENT OFFICE.

EDGAR L. YORK, OF PEORIA, ILLINOIS, ASSIGNOR TO OASIS MANUFACTURING CO., OF PEORIA, ILLINOIS, A CORPORATION.

IRONING MACHINE.

1,403,582.

Specification of Letters Patent. Patented Jan. 17, 1922.

Application filed September 22, 1919. Serial No. 325,495.

To all whom it may concern:

Be it known that I, EDGAR L. YORK, a citizen of the United States, and a resident of Peoria, in the county of Peoria and State of Illinois, have invented certain new and useful Improvements in Ironing Machines, of which the following is a full, clear, and exact description, reference being had to the accompanying drawing, forming part of 10 this specification.

My invention relates to machines for ironing various kinds of clothing and other cloth, and it has for its objects to simplify the arrangement and construction of the 15 machine whereby its operation may be properly controlled; and whereby the machine may be operated either by hand or power, and when operated by power its operation may be instantly started or stopped without the 20 necessity of stopping the motor for operating the machine; and whereby when the machine is in operation, a constant pressure of the heating element will be maintained upon the work passing through the machine; and 25 whereby the ironing element will be self-centering in its relation to the feed roller; and in other features of construction which together with the novelty of my invention will be hereinafter more fully set forth and 30 specifically pointed out in the claims.

In the accompanying drawing:

Fig. 1 is an end view of a machine embodying my invention.

Fig. 2 is a front view of the same.

Fig. 3 is a sectional end view of the ironing element.

Fig. 4 is an enlarged detail partly in section of the clutch for disengaging the feed roller.

Fig. 5 is a detail view of a hand crank and pinion for hand operation of the machine.

The same numerals of reference are used to indicate identical parts in all the figures.

In its preferred form of construction my machine comprises a pair of legs 6 upon which a receiving table 7 is mounted, the latter carrying the brackets 8 and 9. Feed table 10 is carried by the upper portion of the brackets 8 and 9 and the feed roller 11 is suitably journaled in these brackets.

The ironing element 12 is provided with trunnions 13, which pass through the upper ends of bell cranks 14 which in turn are con-

nected through rods 15 to crank arms 16 mounted on a rock shaft 17, the latter being provided with a foot treadle 18.

A tension spring 19, is connected to each bell crank 14 and to the brackets 8 and 9, these springs exerting their tension to move the upper ends of the bell-cranks, and with them, the ironing element 12, toward the feed roller 11.

It is to be noted that the linkage from the bell cranks to the foot treadle is such that when the treadle is released the ironing element recedes from the feed roller.

A pair of lugs 20 are carried by the ironing element and at each end thereof, and located one on each side of the bell cranks 14, the lugs being spaced part to allow a limited oscillating motion of the ironing element 12 so that it may properly center itself against the feed roller 11, the lugs 20 serving to prevent the ironing element from turning in either direction on its trunnions beyond a predetermined amount.

To cause the operation of the feed roller, one of its trunnions is provided with a driving gear 21 (Fig. 4) the gear 21 carrying clutch jaws 22 adapted to be engaged by jaws 23 of clutch hub 24 which is splined on the outer end of the trunnion, the clutch being shown disengaged in Figs. 2 and 4. A shifter 25 is operated by connecting rod 27 which extends to the handle 28, the latter being preferably mounted on the under side of the feed table 10 (Figs. 1 and 2).

The gear 21 is engaged by a worm 29 carried by shaft 30 which is driven by sheave 31 over which the belt 32 passes, the belt also passing over the sheave of the motor 33, the construction and arrangement of parts just described being such that when the motor 33 is set in motion, the clutch 24 may be operated to start or stop the feed roller 11.

Should it be desired to operate the feed roller by hand the same may be accomplished by removing the worm 29 and the shifter 25 and placing the pinion and crank 34 (Fig. 5) upon the stud 35 (Fig. 1) whereupon the gear 21 may be operated, the clutch 24 being left engaged with the gear 21 and the operation started or stopped by merely turning or releasing the crank 34.

Any suitable burner or heating device 36 may be employed to heat the ironing element. To give access to the interior of the

heating element for the purpose of inserting the burner or heater and to afford proper ventilation for the combustion chamber, I provide the rear face of the ironing element with a removable portion 37 which may be provided with a series of openings and which may extend through the greater length of the ironing element, the construction of this feature of the device being 10 shown in Fig. 3.

The feed roller 11 is preferably covered with a cloth or other facing so that its frictional engagement with the work passing through the machine will be sufficient to 15 move the work through the machine.

The operation of the machine is as follows. After having lighted the burner in the ironing element, the operator depresses the treadle 18 and causes it to engage one of the 20 notches 38 (Fig. 2) thereby holding the ironing element away from contact with the feed roller until its temperature has been raised to that desired for the work to be performed. The motor 33 and its connected 25 gearing is next set in motion and a quantity of work arranged on the feed table 10 whereupon the lever 28 may be operated to engage the clutch 24 and cause the rotation of the feed roller 11 and the work on the feed table 30 10 fed toward the roller 11 whereupon the treadle 18 is released from the notches 38 thus permitting the ironing element to assume, through the action of the springs 19, its proper working position. As the work 35 passes through the machine it is collected upon the receiving table 7 from which it may be removed to any suitable place and as the supply upon the table 10 is exhausted the treadle 18 is again depressed until a new 40 supply is secured.

Should it occur that a portion of the work is passing through the machine improperly, the clutch of the feed roller may be disengaged whereby upon this action, the work 45 may be pulled out of the machine and the clutch again re-engaged and the work fed through in a proper manner.

Should it be desired to handle work of an excessively heavy nature or of a plurality of 50 thickness of cloth the work may be carried through a machine in a step by step manner by operating the clutch through its connections as previously described, the clutch being engaged and disengaged periodically, to 55 permit the ironing element to rest for a time

again against any desired portion of the work.

It is to be observed that the ironing element is provided with a concaved face of approximately the same radius as the radius 60 of the feed roller thus providing a large contact between the ironing element and the work handled by the machine.

Having thus fully described my invention, I claim:

1. In an ironing machine the combination of a frame comprising in part feeding and receiving tables, and a work feeding element mounted adjacent the feeding table, clutch controlled driving mechanism for the feeding element, a concaved-face ironing element mounted adjacent the work feeding element, trunnions for carrying the ironing element, movement limits restricting the oscillating motion of the ironing element upon its trunnions, means for yieldingly holding the ironing element against the feed roller, and means for overcoming the latter means to move the ironing element away from the feed roller. 70

2. In an ironing machine the combination of a frame comprising in part a work feeding and a work receiving table, a feeding roller mounted adjacent the feeding table, means for operating the feed roller, a concaved-face ironing element, trunnions for mounting said element adjacent the feed roller and for moving it toward or away from the roller, movement limits for controlling the oscillating motion of the ironing element on 75 its trunnions, means for normally pressing the ironing element toward the feed roller, and foot operated means for moving the ironing element away from the feed roller. 80

3. In an ironing machine the combination of a frame, a feed table carried thereby, a feed roller carried by the frame and adjacent the feed table, a pair of bell-crank carried by the frame, springs for moving the upper ends of the bell-cranks toward the 90 feed roller, a foot pedal and connections to the bell-cranks to overcome the springs and move the upper ends of the bell-cranks away from the feed roller, and an ironing element pivotally mounted at each of its ends to the 100 upper end of each bell-crank and cooperating with the feed roller when the foot pedal is released. 105

EDGAR L. YORK.
